DESIGN.

F. MANKEY.

MOLDING.

No. 16,526.

Patented Feb. 16, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,526, dated February 16, 1886.

Application filed November 2, 1885. Serial No. 181,715. Term of patent 7 years.

To all whom it may concern:

Be it known that I, FREDERICK MANKEY, of Williamsport, Lycoming county, Pennsylvania, have invented and produced a new and original Design for Moldings, of which the following is a specification, reference being had to the accompanying photograph, forming part hereof.

Extending longitudinally the surface of the molding is a raised band, A. The outline of the edges of said band is that of a series of scallops, B, in juxtaposition. Along the center or middle portion of the band are channels C. The part, D, between the channels C is

rounded on its upper surface, and the general appearance of said part is that of a rounded bead extending along the band A.

I claim—

The design for a molding, substantially as herein shown and described, consisting in the raised band A, having edges of reversely curved scalloped outline, and along its middle portion a rounded bead, D.

FREDERICK MANKEY.
